The ornamental design for a bike battery box, as shown and described.

DESCRIPTION

FIG. 1 is a top perspective view of the bike battery box embodied in the present invention;

FIG. 2 is a top view of the bike battery box from FIG. 1; FIG. 3 is a underside view of the bike battery box from FIG. 1;

FIG. 4 is a top view of the diagonal side of the bike battery box from FIG. 2;

FIG. 5 is a top view of the horizontal side of the bike battery box from FIG. 2;

FIG. 6 is a front view of the horizontal side of the bike battery box of FIG. 2;

FIG. 7 is a front view of the vertical side of the bike battery box of FIG. 2; and,

FIG. 8 is an underside view of the bike battery box of FIG. 2.

The dash-dash-dash type broken line shown in FIGS. 1-2 and 4-8 are included for the purpose of illustrating environmental context and forms no part of the claimed design.
